(57) **CLAIM**

The ornamental design for a rod length indicator, substantially as shown and described.

DESCRIPTION

FIG. 1 is a perspective view of a rod length indicator taken from the front, top and left, showing the rod length indicator fully closed;

FIG. 2 is a perspective view thereof taken from the rear, bottom and right;

FIG. 3 is a front elevation view thereof;

FIG. 4 is a rear elevation view thereof;

FIG. 5 is a top plan view thereof;

FIG. 6 is a bottom plan view thereof;

FIG. 7 is a left side elevation view thereof;

FIG. 8 is a right side elevation view thereof;

FIG. 9 is a perspective view taken from the front, top and left side, showing the rod length indicator fully open;

FIG. 10 is a front elevation view showing the rod length indicator fully open;

FIG. 11 is a perspective view taken from the front, top and left side, showing the rod length indicator partially open; and,

FIG. 12 is a perspective view thereof taken from the rear, bottom and right.

The alpha-numeric characters shown in broken lines are for illustrative purposes only and form no part of the claimed design.
